CLAIM

The ornamental design for a skin cover set for a game player, as shown and described.

DESCRIPTION

FIG. 1 is a front view of a skin cover set for a game player showing my new design;

FIG. 2 is a front view thereof, shown in an alternate configuration of use;

FIG. 3 is a rear view thereof, shown in an alternate configuration of use;

FIG. 4 is a left view thereof, showing the skin cover set for a game player in a rotated state;

FIG. 5 is a right view thereof, showing the skin cover set for a game player in a rotated state;

FIG. 6 is a top view thereof, shown in an alternate configuration of use; and,

FIG. 7 is a bottom view thereof, shown in an alternate configuration of use.

The broken lines shown in the figures are for the purpose of illustrating portions of the environmental structure, which form no parts of the claimed design.
